UNITED STATES PATENT OFFICE.

HENRY K. HARKER, CINCINNATI, OHIO, ASSIGNOR TO CHARLES B. SPINNING AND CHARLES S. GALLAGER, BOTH OF SAME PLACE.

SEAL-LOCK.

SPECIFICATION forming part of Letters Patent No. 340,041, dated April 13, 1886.

Application filed January 4, 1886. Serial No. 188,253. (No model.)

To all whom it may concern:

Be it known that I, HENRY K. HARKER, a citizen of the United States, residing at Cincinnati, in the county of Hamilton and State of Ohio, have invented certain new and useful improvements in Devices for Sealing Cars, of which the following is a full, clear, and exact description, reference being had to the accompanying drawings, forming a part of this specification.

My invention relates to an improvement in seal-locks, and is more especially adapted for use on freight-cars, by the use of which the car may be locked by a key containing the number of the station, date, &c., and cannot be opened without breaking and destroying the key. The lock, however, remains intact, and the car can be again locked by simply inserting a new key.

20 The novelty of my invention will be herein set forth, and specifically pointed out in the claims.

In the accompanying drawings, Figure 1 is a perspective view of the lock applied and sealed. Fig. 2 is a front elevation of the pin and key, the pin being cut away to show its internal arrangement. Fig. 3 is a front elevation of the same, showing the key partly inserted. Fig. 4 is the key. Fig. 5 is a front elevation of a modified form, cut away to show the internal arrangement.

The same letters of reference are used to indicate identical parts in all the figures.

A is a hasp, one end of which is fastened to 35 the body of the car and arranged to fit over the staple B, fastened to the car-door when the door is closed. Of course, the staple may be fastened to the body of the car, and the hasp hinged to the door, if preferred.

40 D is a pin which passes through the staple B, so as to inclose the hasp A and lock the car.

C is a chain to prevent the pin D from being lost, one end of it being fastened to the car or door.

45 In order to prevent the withdrawal of the pin D and unlocking of the door, the key E is inserted in the pin below the staple. The pin is provided with an internal chamber, F, the slots G G being the only openings into this 50 chamber. Within the chamber are one or more balls, preferably made of steel; or, if

preferred, a short bolt or plunger may be used, with its lower end beveled, as shown in Fig. 5. The key E is made to fit in the slots G G, and is cut away near its middle, as shown at K. 55 The opening should be made with inclined sides at the top, as at L L, thus forming a sort of funnel, into which the balls or bolt will readily drop by gravity, the opening being enlarged below the shoulders L' L', so that the 60 balls cannot be jolted out. The balls or bolt have a diameter greater than the width of the slot G, and cannot pass through it; hence the key cannot be withdrawn. Where a bolt is used, a circular groove near the lower end 65 (shown at x, Fig. 5) is made to provide shoulders x', which will catch on the under side of the opening in the key and prevent the bolt from being jolted out.

The bottom of the chamber F is flush with 70 the bottom of the slots G G, so that when the key is not in, the bolt or balls rest even with the bottom of the slots.

The key E is made with one end wedge-shaped, and can readily be inserted under the 75 the balls or bolts to raise them, as shown in Fig. 3. As the key is pushed on in, the balls or bolt fall into the opening in the key and effectually seal it. To withdraw the key, it is necessary to break it off. It is therefore made 80 of some brittle or easily frangible metal, so that it can be broken off by a blow. As it is very much weaker at the point of the cut, it will always break near the middle, and the ends can readily be withdrawn. 85

If desired, the bottom of the slots may be made beveled toward the outside, as shown at P, Fig. 5, for the more ready insertion of the key under the balls or bolt.

By having all keys marked with the name 90 or number of the station at which the car is locked, the car cannot be opened and relocked with another key without detection.

The ball or bolts act entirely by gravity, make the lock much more simple and cheap 95 than when springs are used, and much less liable to get out of order, and are always more reliable.

The bolts or balls are completely hidden, so that one unfamiliar with the lock would be 100 unable to learn its construction and operation.

I am aware that seal-locks have been made

with a pin having an internal chamber and spring-actuated bolts, for holding in place a key inserted transversely through slots or openings in the pin, and I do not claim such a construction, nor do I claim, broadly, a seal-lock with a hollow pin carrying internal locking devices; but,

Having thus fully described my invention, what I claim is—

- 10 1. In a seal-lock, the combination, with a transversely-slotted pin provided with an internal chamber carrying a gravitating locking device, of a key adapted to be inserted through said slots, and having its upper edge cut away to form a recess to receive the locking device, said recess being enlarged at its bottom to form retaining shoulders to prevent the withdrawal of the locking device.
- 15 2. In a seal-lock, the combination, with a

transversely-slotted pin provided with an internal chamber carrying one or more gravitating locking balls, of a key adapted to be inserted through said slots, and having its upper edge cut away to form a recess to receive said ball or balls, said recess being enlarged at its bottom to form retaining shoulders to prevent the withdrawal of said ball or balls.

- 20 3. In a seal-lock, the combination, with the pin D, having transverse slots G G, and chamber F, carrying a gravitating locking device, of a key, E, having the cut-out portion K, with shoulders L' L', substantially as and for the purpose specified.

HENRY K. HARKER.
